FLOOR CARE COUPLER

Charles E. Bousquet, 10388 Bassett Drive,
Livonia, Mich. 48950

Filed June 22, 1970, Ser. No. 33,610

Term of patent 14 years

Int. Cl. D15—99; D8—05

U.S. Cl. D37—3

FIG. 1 is a front elevational view of a floor care coupler for power driving a brush or the like from an electric drill at a stand up height;

FIG. 2 is a top plan view of said coupler taken from the line 2—2 of FIG. 1;

FIG. 3 is an enlarged central vertical sectional view of said coupler shown broken; and

FIGS. 4 and 5 are, respectively, horizontal sectional and bottom plan views of said coupler taken, respectively, from the lines 4—4 and 5—5 of FIG. 3.

The brush shown in dash-dot lines in each of FIGS. 1, 2 and 3 is shown for illustrative purposes only; the same applies to the electric drill shown in dash-dot lines in FIG. 1.

I claim:

The ornamental design for a floor care coupler, as shown and described.
